UNITED STATES PATENT OFFICE.

ORREN M. SMITH, OF PHILADELPHIA, PENNSYLVANIA, ASSIGNOR TO SAMUEL W. EVANS AND SAMUEL W. EVANS, JR., OF SAME PLACE.

DESIGN FOR AN UMBRELLA-TIP CUP.

Specification forming part of Design No. 11,310, dated July 29, 1879; application filed June 30, 1879.
[Term of patent 3½ years.]

To all whom it may concern:

Be it known that I, ORREN M. SMITH, of Philadelphia, Pennsylvania, have invented a new and original Design for an Umbrella-Tip Cup, of which the following is a specification.

My design is fully shown in the accompanying drawings, Figure 1 representing the design in connection with a cup with dome top, and Fig. 2 the same in connection with a box-cup having a top comparatively flat, the essential features of the design in each case, however, being unchanged.

The design consists in corrugating the top *a* of the cup, thereby imparting to the same an appearance somewhat similar to what is known as a "Turk's-head."

A subordinate feature of the design is a roughened band or "knurl," *b*, midway or

thereabout between the top and bottom of the cup.

I claim—

1. The design for an umbrella-tip cup, said design comprising the corrugated top *a*, substantially as described, and as shown in and by the accompanying drawings.

2. The design for an umbrella-tip cup, said design comprising the corrugated top *a* and band *b*, substantially as described, and as shown in and by the accompanying drawings.

In testimony whereof I have signed my name to this specification in the presence of two subscribing witnesses.

ORREN M. SMITH.
